JOHN T. FOSTER, OF JERSEY CITY, NEW JERSEY.

Letters Patent No. 62,952, dated March 19, 1867.

MACHINE FOR MAKING PASTEBOARD BOXES.

The Schedule referred to in these Letters Patent and making part of the same.

TO ALL WHOM IT MAY CONCERN:

Be it known that I, JOHN T. FOSTER, of Jersey City, in the county of Hudson, and State of New Jersey, have invented a certain new and useful Improvement on Machines for Making Paper, Pasteboard, and other Boxes or Cases, of which the following is a full, clear, and exact description, reference being had to the accompanying drawing, forming part of this specification, and in which—

Figure 1 represents a plan of the machine.

Figure 2, a longitudinal vertical section thereof; and

Figure 3, a front end view of the same.

Like letters indicate like parts throughout the several figures.

My invention has reference to the manufacture of boxes or cases of paper, or other suitable pliable material, and, as represented in the accompanying drawing, more particularly relates to the manufacture of boxes or cases with open ends, into which a drawer that may be of corresponding material is designed to slide, such as now in use for matches, lozenges, and other articles; and the nature of my invention consists in a combination of a reciprocating feeding bar that takes the blank from an automatically adjustable pile, and a peculiarly constructed former, that, as the blank is drawn or forced through it by the bar, creases and shapes the blank, turning successively the ends or opposite edges of it and causing them to overlap; and furthermore, in combination with these devices, grooved setting disks or wheels that, in the further advance of the blank by the action of the bar through them, sets and gives a square or right-angled finish to the edges of the box or case.

Referring to the accompanying drawing, A represents the frame, which may be of any suitable description, and B the bed or table of the machine. This bed has a slot cut through and across it, forming a delivery aperture or mouth to the pile of blanks b, of or from a vertical box, c, arranged below the bed, the top blank of the pile being continuously, that is, each under blank in succession, kept up to the upper level of the table and against a reciprocating feeding bar, D, by a platform or sliding lifter, E, caused to press continuously upward by means of a spring or weight, F, connected by cord, rope, or chain, e, passing over a pulley, d, with an arm, e, of a socket, f, which is attached to the platen and slides on a guide-rod, g. The feeding bar D has a horizontal reciprocating action on and along the bed, and may work through guides, h h, the front one of which may also serve as a stop and straightener to the top blank of the pile against any tendency of the feeding bar in its back movement to drag it. Any suitable mechanism may be employed to give to the feeding bar its reciprocating motion, say, for instance, a crank, G, pitman, i, and rocking-levers, j k. In the forward end of the bar D is inserted a spring presser-foot or dog, l, made capable of slightly rising and falling, and formed on its pressing face with teeth or gripping formations so shaped as in the advance feed of the bar D to lay hold of a paper blank and carry it forward, but in the back stroke of it to pass easily over or only slightly press in a backward direction on the next top blank of the pile in passing over it. The former, through which the blank thus taken from the pile is dragged or forced, consists of cheeks, H H, made with slightly flaring and curved or sloping front edges, m m, vertical sides, n n, and curved or spiral folders, r r', the one of which is in advance of the other. As the blank carried forward by the feeding bar D strikes at its front edges the edges m m, it is bent or turned up on either side of the bar, and as it strikes and passes the forward folder r its one end or edge is gradually creased and bent over the upper edge of the bar, and afterward, in passing the other folder r', its opposite end similarly creased and bent over so as to overlap the first bent end or edge. The box or case thus shaped is, by the continuing advance of the bar D, forced or carried out of the former and through between angularly arranged grooved setting disks or wheels, S S S S, which give the set or finish to the several bends of the box or case by bearing down on the corners or edges and faces of the bends as the box or case is carried in a tight or close manner in between and through them. Thus set, the box or case may be slipped off the forward end of the bar D, or be forced therefrom in the back action of the latter by the ends of the loose box striking the wheels S S S S and withdrawal of the bar from the box. The same action is repeated till the several blanks in a pile are worked up, when, or before, additional blanks may be inserted in the box C. The boxes or cases thus formed have their overlapping edges afterward gummed or secured in the usual or any suitable manner.

What I claim as my invention, and desire to secure by Letters Patent, is—

1. The combination, with the reciprocating feeding bar D, of a former, so constructed as that in the one motion of the bar the blank is creased and bent over the same and its one edge or end made to overlap the other, substantially as specified.
2. The combination, with the reciprocating feeding bar D and former, operating as described, of setting disks or wheels, arranged to act on the bent edges of the box or case as it is delivered from the former, essentially as herein set forth.

J. T. FOSTER.
